UNITED STATES PATENT OFFICE.

THÉOPHILE HARANG, OF NEW ORLEANS, LOUISIANA.

APPARATUS FOR THE DISINTEGRATION OF BAGASSE AND OTHER VEGETABLE MATTER.

SPECIFICATION forming part of Letters Patent No. 278,545, dated May 29, 1883.

Application filed January 18, 1883. (No model.)

To all whom it may concern:

Be it known that I, THÉOPHILE HARANG, of New Orleans, in the parish of Orleans and State of Louisiana, have invented a new and Improved Apparatus for the Disintegration of Bagasse and other Vegetable Matter, of which the following is a full, clear, and exact description.

The object of my invention is to provide a new and improved apparatus for extracting the fiber from cane, leaves, sorghum, or any other plant, in such a manner that the said fiber can be used for industrial purposes in the same manner as any other of the well-known fibers derived from plants.

Reference is to be had to the accompanying drawings, forming a part of this specification, in which similar letters of reference indicate corresponding parts in all the figures.

Figure 1 is a longitudinal elevation of the revolving platform carrying the boxes for receiving the bagasse or other material, parts of the conveyers and of the steam and water pipes being shown. Fig. 2 is a plan view of the same. Fig. 3 is a longitudinal elevation of the devices for crushing and breaking the bagasse or other material before it is washed, and an end elevation of a row of washing-tanks. Fig. 4 is a plan view of the same. Fig. 5 is a longitudinal sectional elevation of one of the tanks. Fig. 6 is a cross-sectional elevation of the device for crushing and breaking the bagasse.

On a platform, A, adapted to revolve in the horizontal plane on a base, B, a series of boxes C, provided with removable lids, are arranged radially, as shown. The platform A is provided with suitable rollers or wheels, a, which rest on the base B and support the said platform A.

One or more pipes, D, extend from the inner end of each box C to a pipe, E, at the center of the platform A, and into the pipe E a smaller pipe, F, projects in such a manner that the pipe E can rotate around the pipe F, the two pipes being suitably packed at the joints to prevent leakage. The exhaust-steam of the engine is conducted through the pipes F, D, and E to the boxes C. The steam escaping from the safety-valve of the boiler is conducted to the pipe F through a branch pipe, G. A conveyer-belt, H, is contained in a frame, J,

provided with a downwardly-projecting spout, K, the lower end of which projects over the outer edge of the platform A. The belt H is operated by suitable devices and extends from the cane-crushing mill to the platform A, or from any other locality to the platform A, as it is used to carry the cane or other vegetable matter from which the fiber is to be extracted to the platform A, on which the said cane or other material is subjected to the first operation. A water-pipe, L, is so arranged that its lower end will be above the platform A, as shown in Figs. 1 and 2. A side carrier, M, provided with an endless belt, M', extends from the platform A to the crushing apparatus N. The carrier M is provided at the end toward the platform A with a spout, N', upon which the bagasse is emptied as it is drawn from the boxes C, and then passes through the said spout upon the conveyer-belt M'. The crushing apparatus N consists of a large wheel, O, held in a frame or casing, P, provided with a semicircular top, P'. In the casing or frame P a series of rollers, Q, are journaled, which are in contact with the outer circular surface of the wheel O, and between each two rollers spouts or nozzles R project from water-pipes contained in the semicircular top P' of the frame P. The water is fed to the pipes in the semicircular top P' and to the spouts R through a pipe, R'. A comb wheel, S, is journaled in the frame P at the end opposite the one at which the end of the conveyer M' is located, and directly below the said comb-wheel the spout S' is provided, from which the disintegrated bagasse or pulp passes upon a conveyer-belt, T, and is conveyed to the several washing-tanks V, which are provided with a false bottom, W, into the space below which steam is conducted through pipes W'. A pipe, U, provided with a faucet or cock, U', for each tank V, extends transversely over the same, and supplies the tanks with sufficient water for washing the bagasse.

The operation is as follows: The crushed cane, sorghum, or other vegetable matter from which the fiber is to be extracted is conveyed from the mill or other place to the platform A, and slides from the end of the belt H down the spout K into one of the boxes C, the lid of which has been withdrawn. Then the box

is closed, and by means of a crank operated by machinery or by some other suitable device the platform A is turned so that the next box C will be below the spout K, and a quantity 5 of lime-water and caustic-soda solution is conducted through the pipe L into the box that has just been filled, which lime-water and caustic-soda solution is contained in a suitable tank, from which it can flow into the pipe L. 10 In place of using the lime-water and soda solution, a quantity of slaked lime and pulverized caustic soda can be sifted upon the bagasse in the box; but I prefer to use lime-water and caustic-soda solution. In the above-described 15 manner the several boxes C are successively filled with bagasse, which is treated with lime-water and caustic-soda solution, and while one box is being filled the bagasse in the other boxes is being operated upon by the lime-water 20 and caustic-soda solution, and by the heat of the steam which passes from the exhaust-pipe F through the pipes E and D to the several boxes, and thereby the bagasse will be thoroughly impregnated with lime and soda. After 25 each box has made one revolution and again arrives at the spout K it is opened, its contents are emptied upon the spout M and side carrier, M', and are conducted by the same to the crushing apparatus N. The box C can 30 be emptied by hand or by machinery, as may be desired. The conveyer M carries the bagasse to the crushing apparatus N, where it passes to the periphery of the wheel O and the rollers Q and is crushed. Between each two 35 rollers Q—that is, after every time it has been crushed—the bagasse or pulp is washed by streams of water issuing from the spouts R.

After leaving the last roller Q the pulp or bagasse comes in contact with the comb-wheel S, which seizes it and dishevels it. Then the 40 bagasse drops upon the spout S', and is carried by the conveyer T to the several tanks V, in which it is placed. In the said tanks the bagasse is heated by the exhaust-steam, which is conveyed into the space below the false bottoms W by the pipes W'. The steam passing through the perforated false bottoms W causes the disintegrated mass to rise to the surface, where it is washed by the water issuing from the cocks U' on the pipe U. The fibers are 45 then used in the same manner as other vegetable fibers, and for various purposes. 50

Having thus fully described my invention, I claim as new and desire to secure by Letters Patent—

1. The combination of a rotary platform carrying the radial bagasse-holders C, the rotary pipe E, and the fixed pipe F, connecting with the steam-supply, with a superposed soda and lime supply pipe, L, whereby the bagasse 60 may be treated with steam, lime, and soda, as described.

2. In an apparatus for disintegrating bagasse and other vegetable matter, the combination, with the frame or casing P, of the top 65 P', the wheel O, the rollers Q, the comb-wheel S, and the spouts R between each two rollers Q, substantially as herein shown and described, and for the purpose set forth.

THÉOPHILE HARANG.
